UNITED STATES PATENT OFFICE.

JOHN C. GOOLD, OF ALBANY, NEW YORK.

DESIGN FOR A LANDAU-SLEIGH.

SPECIFICATION forming part of Design No. 13,541, dated January 23, 1883.

Application filed October 20, 1882. Term of patent 7 years.

To all whom it may concern:

Be it known that I, JOHN C. GOOLD, a citizen of the United States, residing at Albany, in the county of Albany and State of New York, have invented and produced a new and original Design for Landau-Sleighs, of which the following is a specification, reference being had to the accompanying drawings, forming part thereof.

Figure 1 is a side elevation of my newly-designed landau-sleigh with the top up; and Fig. 2 is a side elevation of the same with the top turned down.

Heretofore landau-sleighs have been made which presented an upwardly-curved lower border-line of edge to the front portion of the swell side panel, and to the upper edge of the forward portion of said panel either a broken concave line of upper border-edge or a border-edge which is continuous with the upwardly-curving line of the upper edge of said panel and terminates at the point of termination of the said upwardly-curved border-line of the lower edge of same. The rocker or sunk bottom presented a continuous extension from the front knee to a point rearward of the back knee, with its rear end terminating with a vertical line of end surface. The side belts presented the appearance of an unbroken extension from front to rear, with its lower border-edge made either with a continuous upwardly-curving line forward or with a second curved line, which is made on a different and shorter curve running forward and upward, and with its portion of upper border-edge forming the lower line of the doorway of the sleigh made with a concave form of curved line, which sinks at its middle of length about one-half of the depth of said belt, and the doorways presented merely an opening, which extended from the flap at the top of the doorway down to the concave line of the lower side of the same in the belt, and when solid doors have been used they have presented the appearance of passing down through the swell side panels and terminating at the upper line of the rocker below, or they terminated at about the middle of the depth of the belt and above said side panels, with a portion of each door-post projecting upward above the line of the turned-down portions of the door-posts, attached to the top, when said top was turned wholly down,

and when the sections of the top were turned wholly down the horizontal lines of the turned-down sides of the doorway had the appearance of ending at the side edges of the portion of the doorway, curving down into the belt or not being continuous with the top edge-line of the door proper when a door was in fact employed.

The leading features of my new design consist in the shapes and conformations of the several portions of the body of the sleigh, in its connection with the top, in which outlines of the several portions of the body will have the appearance of continuity of graceful curved lines, and also curved and straight lines combined together to give harmony of separating lines to relieve the body from a heavy appearance and to give a pleasing contrast of arrangement of the sections of the top with the portions of the body, whether the former are in a standing position or are folded down.

In the drawings, A represents the runners of the sleigh, curving upward in front and then bending forward and terminating with the lower side of straight bracket b of toe-board B, with the small curved portion a of the runner appearing to be continued with the bracket, as shown.

C is the usual swell side panel of the body of the sleigh. The lower border-edge of said panel is made with curved or concave line c, running from the rear end of the body of the sleigh forward and terminating with a slightly-reversed-curved line, c', at point c' at the base of bracket b, and bordered by molding C', having a corresponding form of line.

F is the rocker or sunk bottom, which is made to extend from the rear of the middle knee, k, to a point a little rearward of the back knee, k', with its lower outline of edge made with straight line e and its upper outline corresponding with curved line c of panel C, and its rear end with concave line e², which concave line will, with the rear portion of the curved outlines of panel C, form in appearance an ogee line, e², as shown.

D is the belt, which, though broken by the door passing through it, has the appearance of being made continuous from front to rear, and with its lower border-edge line made with a continuous curved or concave line, c², from rear to near its front termination, when it is made to curve

over

in a reverse direction in a convex line, c^3 , which terminates at point c^4 , the point of front termination of the lower border-edge line, $c\ c'$, of the swell side panel, C. The lower border-line of belt D forms the upper border-line of panel C. The forward portion of belt D is extended about four or five inches above the plane of the front end of toe-board B, and is made with a straight uppermost line, which is considerably shorter than the width of the dickey-seat E, and its front end is made with a concave line of border-edge, d , running downward and forward from the straight top line, covered by the dickey-seat, to the base of bracket of toe-board B, as shown. The border-outline of the upper and rear edge of belt D (rearward of dickey-seat E) extends from the bottom side of the dickey-seat with a flat curved outline, d' , falling in with a sharper curved line, d^2 , 20 and running thence rearward, with an easy, flat concave or curved line, d^3 , to the rear end of the body of the sleigh. With the said belt made with outlines above and below, with said curved lines $c\ c'$ and d' , d^2 , and d^3 , as shown and 25 above described, it is made to have the appearance of an upwardly-curved and gradually-tapering panel extending from the toe-board and dickey-seat in front to the rear end of the body of the sleigh, with its portion rearward 30 of the dickey-seat narrow and light in appearance, and its forward portion beneath that seat appearing to harmonize and balance with the rearward portion of the body of the sleigh.

G is the crest-panel beneath the dickey-seat, 35 having its shape and conformation of outline made corresponding with that of the portion of belt D forward of the door, as by outlines $g\ g'\ g^2$, made parallel with the outlines d , d' , d^2 , d^3 , and $c^2\ c^3$. The said crest-panel may be made 40 to appear raised or sunken or bordered by a molding or bead, as may be preferred.

Between the dickey-seat and the rear end of the body of the sleigh and above the appearing belt D are panels H H' and H², which 45 have their outlines of lower edges formed by the concave or curved lines of the upper edge of the apparent belt D, as by lines d^3 . The outlines of the upper edges of said panels are made with straight horizontal lines h, formed 50 on the same plane and appearing to be continuous save by the moldings m of the sides of the door, running vertically through said line of upper edge and downward to the upper edge of the swell-side panel. The form of the out- 55 line of the forward end of panel H is made with a sharp curved or concave line, h' , turning forward and gradually intersecting with the curved line d^2 of belt D, so as to appear to form, with line d' , a section of an oval, as shown. 60 These panels H H' H² are made to appear to intervene between the belt-panels and the leather of the top, and enables the top to be presented with a less vertical height than heretofore appearing above the upper line of the 65 body proper of the sleigh.

The door I is made to appear to extend from the lower outline of the belt D up to the drip

of the top, as to i, when the top is up, as in Fig. 1, and upward only to molding n when the top is down, as in Fig. 2, and when the top 70 T is up the door appears to include several panels of narrow width in its lower portion, and a window (which may be closed by a sash working within the door proper) in its upper portion in the top sections of the sleigh. 75

The door-posts m' m', forming the sides of the window-section of the door, are made to form the oppositely-facing outline-edges of the top sections when the forward and rearward sections of the top are up, as in Fig. 1, and 80 when the said sections of the top are turned down, as in Fig. 2, the said door-posts are made to appear as horizontal bars which outline the upper edges of said top sections, as they are made to appear to be extended, re- 85 spectively, forward and rearward from the molded upper bar, n, of the door I proper, while the said door will be made to appear to be contained wholly in the body of the sleigh and terminate at said bar n, while when the 90 sections of the top are up, as shown in Fig. 1, the said door-posts are made to appear as being a continuation of door I, to give to the door the appearance of being contained partly in the body of the sleigh and partly in the standing 95 top. When the sections of the top are turned down the line of the upper edges of the turned down door-posts m' m' and molded upper bar, n, of the door will appear to be about on a line parallel with the line of moldings h h h, which 100 outline panels H H' H² below, as shown in Fig. 2, and this apparent continuous upper horizontal outline edge (formed by posts m' m' and bar n) will be on a line slightly below an imaginary line drawn on a horizontal plane 105 with the lower edge of the skirt of the dickey-seat, and slightly above an imaginary line drawn on a horizontal plane with the upper and forward end of the toe-board of the sleigh.

It will be readily observed that the short 110 curve a of the runner appears to run into the straight line of the lower side of the bracket of the toe-board, and in an opposite direction run to the reversed and larger curve of the front portion of the runner, and form, with such 115 larger curve, an ogee line of curves, and also that the lower line of bracket b of the toe-board, together with curved lines c' and c of molding C', bordering the lower edge of the swell side panel, presents the reversed curves 120 of a flattened ogee, which presents a pleasing contrast with the more sharp curves of ogee formed by the curve a of the runner and the larger curves below of the same.

The upper curved lines, $d\ d^2\ d^3$, presented 125 as bounding the belt-panels D, may be formed by an incised edge or by a bead or molding, or by other means practiced by the trade to give shape and conformation to panels, and the door may be made to appear to extend 130 downward through the swell side panel, or to near molding C', if preferred, provided the curve c^2 of the upper edge of said panel is made to appear to extend from rear to and

through the door and continue to run forward, $\frac{1}{4}$ line, d^3 , of panels H and H^2 , intervening between said belt-panels and top T , in which the upper edge of panels H H^2 will be made to

present horizontal lines h h on the same plane 50 with each other, and said panels made to appear to increase the vertical depth of the body of the sleigh below the said top and reduce the length of upward extension of the latter above the former, substantially as shown and 55 described.

7. In a landau-sleigh presenting the appearance of having swell side panels, C , belt-panels D , a leather top, panels H H^2 , intermediate between said top and belt-panels, and 60 door I , the combination, with said appearing portions, of door-posts m' m' , appearing to be made with the oppositely-facing marginal edges of the respective sections of said leather top, whereby there is produced the appearance, 65 when the sections of the top are up, of a door made partly in the body proper of the sleigh and partly in the top, and when said sections are turned down there is produced the appearance of the door being contained wholly in the 70 body proper of the sleigh, with its top terminating at the molded bar n on a line with the horizontal plane of the upper edges of the down-turned door-posts m' m' , with the line of the upper edges of posts m' m' and bar n appearing 75 to be on a horizontal line parallel with the line of the upper edges of panels H H' H^2 , substantially as shown and described.

8. The shape and conformation of the body of a sleigh, in which the belt-panel D will 80 present the appearance of being made to run rearward from the dickey-seat with a slightly-downward-curved tapering form, and of being situated between a swell side panel below and panels H H^2 above, and its front portion 85 made to present curves d and d' d^2 , with curve d running downward and forward to the toe-board, substantially as shown and described.

JOHN C. GOOLD.

Witnesses:

WILLIAM M. GILBERT,

ALEX. SELKIRK.

as shown.

I claim—

1. In a landau-sleigh, the shape and conformation of the upper front portion, a , of runner A , and lower side outline of bracket b of toe-board B , in which the curve of portion a appears to be gradually lost in the straight line of said bracket, and, with the larger upper turned curve of runner A present the reversed curves of an ogee, substantially as shown and described.

2. The shape and conformation of the lower line of swell side panel C and its bordering molding C' , in which the said bordering molding will be made to present curved lines c and c' , running by an easy curve into the straight line of the lower edge of bracket b of the toe-board, substantially as shown and described.

3. The shape and conformation of the swell side panel C from rear to front, in which its lower line of edge will be made to present curved lines c c' and its upper edge curved lines c^2 c^3 , meeting forward at point c^4 , substantially as shown and described.

4. The shape and conformation of the rocker F , in which the lower edge of the same will be made to present a straight line extending to the middle knee, and its upper edge a curved line corresponding with the curve of molding C' , and its rear end a concave curve, e^2 , which will, with curved line c of molding C' , present the appearance of an ogee, c e^2 , substantially as shown and described.

5. The shape and conformation of belt-panel D , in which will be presented the curved line of upper edge, d d^2 d^3 , extending from the rear of the straight line of support of the dickey-seat back to the rear end of the body of the sleigh and the curved lower border-outline, c^2 and c^3 , causing said belt-panel to appear as being a tapering panel gradually curving upward and rearwardly from its heavier front portion, substantially as shown and described.

6. In a landau-sleigh, the combination, with belt-panel D , presenting a curved upper out-
